UNITED STATES PATENT OFFICE.

WILLIAM E. WOODARD, OF FOREST HILLS, NEW YORK, ASSIGNOR TO FRANKLIN RAILWAY SUPPLY COMPANY, A CORPORATION OF DELAWARE.

TRUCK FOR RAILWAY VEHICLES.

Application filed December 23, 1921. Serial No. 524,341.

To all whom it may concern:

Be it known that I, WILLIAM E. WOODARD, a citizen of the United States, residing at Forest Hills, in the county of Queens and State of New York, have invented certain new and useful Improvements in Trucks for Railway Vehicles, of which the following is a specification.

This invention relates to trucks for railway vehicles and it is particularly useful in locomotive engine trucks. The invention has to do with that type of truck known as a "lateral motion" truck and is an improvement on the invention patented to me April 15, 1913, No. 1,060,222.

In the construction shown in such patent, centering rockers are interposed between the bolster and truck frame, the bolster having four lower surfaces contacting with four rocker surfaces, i. e., the bolster has four points of support. Difficulty has been encountered with this construction because of the inability of securing a perfect contact at the four points of support. This results, among other things, in uneven and twisting stresses on the parts and also in uneven wear, which latter is usually of such character as to increase the inequality and instability of the support. I have further more found that there is additional wear on the bearing surfaces resulting from the abrasive action when the bearing surfaces move on each other.

The nature of the difficulties above mentioned will be readily understood on considering the severe vibration and pounding to which rolling stock of this character is subject.

One of the primary objects of my invention is to overcome the difficulties referred to and to secure certain additional advantages which will be hereinafter pointed out more particularly.

I accomplish the foregoing by means of a construction, the preferred embodiments of which I have illustrated in the accompanying drawings, wherein:

Fig. 1 is a plan view of a truck embodying my improvements; Fig. 2 is a section taken on the line 2—2 of Fig. 1; Fig. 3 is a bottom plan view of the bolster, drawn on an enlarged scale; Fig. 4 is a top plan view of an improved form of centering rocker forming a part of my invention; Fig. 5 is

an enlarged fragmentary sectional view of the centering parts, taken on the line 5—5 of Fig. 6; Fig. 6 is a section taken on the line 6—6 of Fig. 5; and Fig. 7 is a section taken on the line 7—7 of Fig. 6 but illustrating the parts in another position.

Referring now to Figs. 1 and 2, particularly, it will be seen that the truck is of usual construction and it will suffice for the purposes of this specification to make reference to the center pin 7; the bolster A having a center plate 8 for the reception of the center pin; and the transom or bolster support 9, extending between the side frames 10 of the truck.

Referring now to Figs. 3 and 5, particularly, it will be seen that the bolster A is constructed so as to have three depending centering rocker bearing portions *d*, *e*, *f*, with inverted V-shaped bearing surfaces 11. The bearing portions *d* and *e*, as will be seen on inspection of Fig. 3, are located at opposite edges of the bolster, on one side of the center line thereof and in substantial alinement. The third bearing portion *f* is arranged on the other side of the center line 80 of the bolster and comes opposite the space *g* between the bearing portions *d* and *e*. The bearing portion *f* is approximately equal to the combined dimensions of the portions *d* and *e* so that the total bearing surfaces presented are equal in area. Along their inner edges the portions *d* and *e* are provided with a plurality of recesses or pockets 12, and the portion *f* has similar pockets at its ends, arranged in alinement with the pockets in the portions *d* and *e*.

The construction of the centering rockers will now be described. These rockers, indicated as a whole by the reference letter B, are provided with three bearing surfaces *h*, *i*, *j*, which are suitably spaced apart and are of such dimension as to correspond with the bearing surfaces of the portions *d*, *f* and *e*, respectively. Between bearing surfaces, the centering rockers are provided with a plurality of teeth or knobs 13 adapted to fit into the recesses 12, for a purpose which will be set forth. Each rocker is provided with journal portions 14 adapted to take seat in the seats 15 of bearing strips 16 supported in the centering rocker pocket of the bolster support. The rockers are ribbed longitudinally between channels, as indicated at 17

in Figs. 5 and 6, and they are transversely strengthened by the ribs or webs 18, making a light, but very strong construction.

It will be seen from the foregoing that when two rockers are interposed between the bolster and the bolster supports, the portions *d* and *e* will bear upon the end bearing surfaces *h* and *j* of one rocker, while the portion *f* will bear upon the middle bearing surface *i* of the other rocker, whereby a three-point support is provided for the bolster which, therefore, will always have a proper, stable support. It will also be noted that the construction is such that it is possible to use counterpart rockers, thus avoiding the necessity of making right and left-hand rockers. Where it is necessary to recess the rocker, as indicated at 20, in order to accommodate the pin 21, it will be seen that they may be fitted into place by simply reversing a pair of rockers, end for end.

It will be seen from the foregoing that the support afforded by the arrangement described is such as to assure stability and to avoid excessive wear of uneven character as is noticeable where the support is unstable. Furthermore, it will be seen that the life of the parts is extended for when wear has gone to undesirable lengths, fresh bearing surfaces will be presented to the parts *d*, *e* and *f* by simply interchanging the rockers. The excessive wear resulting from the abrasive action incident to the rockers and bolsters shifting relative to one another during lateral motion, is obviated by the inter-engaging portions 12 and 13 which tend to produce a more or less true rolling action, without slipping or relative shifting of bolster and rockers.

Fresh bearing surfaces may be also presented by simply reversing the position of the bolster. The arrangement is also such that practically 50% of the length of the rocker is utilized for bearing surfaces, affording a material increase over older designs.

What I claim is:

1. In a lateral motion railway vehicle truck, a bolster having three bearing surfaces for centering rockers, two of said surfaces being on one side of the center line of the bolster and spaced apart and the third surface being on the opposite side and arranged opposite the space between the other surfaces.

2. In a lateral motion railway vehicle truck, a bolster having three bearing surfaces for centering rockers, arranged so that with two centering rockers, two of the surfaces bear on one rocker and the third surface on the other rocker providing a three-point support.

3. In a lateral motion railway vehicle truck, a bolster having three bearing surfaces for centering rockers in its lower face

in combination with two substantially counterpart centering rockers each having three bearing surfaces arranged in a line, the bearing surfaces on the bolster being so arranged that two of them bear on the end surfaces of one rocker and the third surface bearing on the middle surface of the other rocker.

4. In a lateral motion railway vehicle truck, a bolster having three bearing surfaces for centering rockers, in its lower face in combination with two substantially counterpart centering rockers each having three bearing surfaces arranged in a line, the bearing surfaces on the bolster being so arranged that two of them bear on the end surfaces of one rocker and the third surface bearing on the middle surface of the other rocker, such third surface and the middle surfaces of the rockers being of greater length than the other surfaces.

5. In a lateral motion railway vehicle truck, a bolster having its lower part so formed as to provide three centering rocker bearing surfaces located below adjacent portions of the bolster, two of said surfaces being arranged substantially in line and spaced apart and the third being opposite the space between the other two.

6. In a lateral motion railway vehicle truck having a bolster, a centering rocker having three bearing surfaces for the bolster arranged in substantial alinement and spaced apart longitudinally.

7. In a lateral motion railway vehicle truck having a bolster, a centering rocker having three bearing surfaces for the bolster arranged in substantial alinement and spaced apart longitudinally, together with means between the surfaces for engaging the bolster to prevent relative shifting.

8. In a lateral motion railway vehicle truck a bolster and a centering rocker having bearing surfaces, and interengaging means on bolster and rocker to prevent relative shifting during rocking, said means consisting of a plurality of projections on the rocker and a plurality of corresponding recesses on the bolster.

9. In a lateral motion railway vehicle truck, a bolster having three centering rocker bearing portions two of which are arranged substantially in line and spaced apart and provided with a plurality of recesses at their inner ends, and the third of which is disposed opposite the space between the said two and is provided at its ends with a plurality of recesses substantially alining with said first mentioned recesses, in combination with two substantially counterpart rockers each having three spaced bearing portions with a plurality of projections therebetween and complementary to said recesses.

10. In a lateral motion railway vehicle

truck, a bolster having three depending centering rocker bearing portions arranged so that with two centering rockers, two of said portions bear on one rocker and 5 the remaining portion on the other rocker to provide a three-point support.

11. In a lateral motion railway vehicle truck, the combination of a bolster having centering rocker bearing surfaces, and a 10 plurality of centering rockers, said surfaces and rockers being so disposed as to provide a three-point support for the bolster.

12. In a lateral motion railway vehicle truck, a bolster having three centering 15 rocker bearing surfaces, the area of one of said surfaces being substantially equal to the combined areas of the other two.

13. In a lateral motion railway vehicle truck, a centering rocker having three bolster 20 supporting surfaces, the area of one of which is substantially equal to the combined areas of the other two.

14. In a lateral motion railway vehicle

truck, a bolster having three centering rocker bearing surfaces, and two substantially 25 counterpart centering rockers each having a bolster bearing portion of length substantially equal to the combined lengths of the three bolster centering rocker bearing surfaces.

15. In a lateral motion railway vehicle truck, the combination of a bolster and supporting means between the bolster and the truck arranged to provide a three-point support for the bolster, said supporting means 30 permitting lateral motion of the bolster.

16. In a lateral motion railway vehicle truck, the combination of a bolster and a rocker, the bolster and rocker having bearing 40 surfaces so disposed that fresh bearing surface is presented when the bolster and rocker are arranged in relatively reversed relation.

In testimony whereof, I have hereunto signed my name.

WILLIAM E. WOODARD.
